UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL-STOVE.

1,367,393.

Specification of Letters Patent.

Patented Feb. 1, 1921.

Application filed July 17, 1919. Serial No. 311,482.

To all whom it may concern:

Be it known that I, RUDOLPH HOFFMAN, a citizen of the United States, residing at Kankakee, in the county of Kankakee and State of Illinois, have invented certain new and useful Improvements in Oil-Stoves, of which the following is a specification.

The invention relates to oil stoves and more particularly to improved means for 10 mounting the oil reservoir thereof, the aim being to provide means of extremely simple construction and operation for supporting the reservoir of the stove in such a manner that it will be securely held in place but may 15 be quickly and easily removed for the purpose of replenishing the supply of oil or for other purposes.

In the accompanying drawings, wherein 20 I have illustrated a preferred embodiment of my invention, Figure 1 is a fragmentary top plan view of a stove embodying the features of my invention, but with the reservoir removed. Fig. 2 is a central sectional view taken on line 2—2 of Fig. 1. Fig. 3 25 is a fragmentary vertical section taken on line 3—3 of Fig. 2.

In the drawings 1 indicates a portion of one end of a stove frame having secured thereto a bracket 2, and 3 designates the 30 lower portion of a tank or reservoir adapted to be supported upon the bracket. 4 is an oil well mounted upon the underside of the bracket 2, and 5 is a pipe leading from the reservoir to the stove burners (not shown).

35 The bracket 2 comprises an upright portion 2^a secured to the stove frame 1 as by means of screws 6, and a horizontal portion or ledge 2^b projecting outwardly from the frame 1. At the upper end of the upright 40 portion 2^a the bracket has an outwardly projecting flange 2^c against which the reservoir is adapted to abut and thus be held in its proper position relative to the frame.

The reservoir 3 may be of any preferred 45 construction. Herein it is shown in the form of a glass bottle having a neck 7 upon the lower end of which is suitably secured an annular metallic member 8 having a bottom 9 with an aperture 10 therein. Secured 50 to said annular member 8 is a cup-shaped member 11 having an annular flange 12 at its peripheral edge. An opening 13 is provided in the bracket portion 2^b adapted to receive said cup-shaped member 11 with the

flange 12 resting upon the upper edge of the 55 opening (Fig. 2). The neck 7 of the reservoir 3 thus depends into the well 4.

The well 4 may be secured upon the underside of the horizontal portion 2^b of the bracket in any suitable way; and the pipe 5 60 opens into the bottom of the well near one edge thereof and leads inwardly through the stove frame 1. The pipe thus assists the bracket 2 in supporting the reservoir 3 and associated parts.

When the reservoir 3 is supported in position upon the bracket, oil is permitted to flow therefrom freely into the well 4, but means are provided so that when the reservoir is removed from its support the flow of 70 oil therefrom is immediately cut off. This means herein comprises a valve member 14 mounted upon a stem 15 and arranged to seat upon the edge of the opening 10 in the bottom plate 9 of the annular member 8. A 75 spring 16 bearing between said valve member and a cage 17 entered within the neck and secured to said plate 9 normally tends to seat the valve member 14. The parts are so arranged, however, that when the reservoir 80 is in its operative position the valve stem engages with the bottom of the well 4 and holds the valve member 14, against the action of the spring 16, in its raised position.

The means for securing the reservoir 3 in 85 position upon the bracket 2 preferably comprises a horizontal slide member or sleeve 18. This member is substantially rectangular in form and is adapted to substantially surround the well 4 and horizontal portion 90 2^b of the bracket. Thus it comprises a top wall 19, side walls 20, a bottom wall 21 and a forward end wall 22. In the upper wall 19 is provided an elongated aperture 23 and in the bottom wall 21 is provided a slot 24. 95 Said aperture and slot are arranged to permit of sliding movement of the member 18 relative to the reservoir 3 and pipe 5; and the aperture 23 is shaped so that when the member 18 is in its innermost or operative 100 position the reservoir 3 is held against removal by the top wall of the member engaging with the flange 12 of the cup-shaped member 11 seated upon the horizontal portion 2^b of the bracket and when the member 18 is moved to its outer or inoperative position, the cup-shaped member 11 may be withdrawn through the aperture 23. To this

end the forward portion of the aperture 23 is made of a size substantially less than the diameter of the cup member 11, and at the rear end of the aperture it is made of a size 5 slightly greater than the diameter of the member 11 (Fig. 1). To afford a convenient hold for the fingers of the operator in operating the slide, the forward wall thereof may be extended downwardly below the bottom wall 21, as at 22^a.

As a means for limiting the outward sliding movement of the member 18, I provide a stop member 25 in the form of a strap entered through a slot in the upright portion 15 2^a of the bracket immediately above the horizontal portion 2^b and bent rearwardly upon the underside of said portion 2^b and secured thereto. At its forward end the strap is bent upwardly to form a hook member 25^a located a substantial distance forwardly of the rear end of the aperture 23 in the normal position of the member 18. It will be seen that as the member 18 is slid forwardly relative to the bracket portion 2^b and the 20 reservoir 3 thereon, that the rear edge of the aperture 23 will engage with the hook portion 25^a of the stop member 25, and the parts are relatively arranged so that the forward movement of the member is limited 25 just as the enlarged portion of the aperture 23 comes into register with the aperture 13 (broken lines Fig. 1), upon the edge of which is seated the flange 12 of the cup member 11. In this position of the parts 30 it will be seen that the reservoir may be readily withdrawn upwardly, the cup member 11 passing through the enlarged portion of the aperture 23. When the slide is in this position, the portion 25^a of the stop 35 member is arranged to engage in a notch 23^a formed in the top plate 19 at the rear edge of the aperture 23 (Fig. 1). To again lock the reservoir in position it will be apparent that it is only necessary to insert the cup 40 member into place with its flange resting upon the edge of the aperture 13 and then slide the member 18 rearwardly into the position shown in full lines in Fig. 1 when the restricted portion of the aperture 23 overlies the cup 11. In this operation, the stop 45 member 25, by reason of the engagement of the flange 12 of the cup member with the forward edge of the hook portion 25^a of the stop member, also serves to assist in holding 50 the cup member in position while the member 18 is slid rearwardly. This arrangement is particularly advantageous in the event that the member 11 is so shaped that it will not engage with the edge of the aperture 13 as herein shown.

It will be seen that I have provided means of a practical character for supporting the oil tank or reservoir of an oil stove. The operation of removing the reservoir is 55 extremely simple as is also the construction

thereof. An efficient device is accordingly produced which may be manufactured at a minimum cost.

While I have herein illustrated and described the invention with considerable particularity, I desire to have it understood that in the interpretation of the appended claims they are not to be limited except as may be necessitated by the state of the prior art.

I claim as my invention:

1. In an oil stove, an oil reservoir, and a support therefor comprising a horizontal supporting ledge, an oil well fixed on the underside of said ledge, said ledge having an opening therein, said reservoir having a downwardly projecting discharge nozzle with an outwardly projecting member adapted to be seated upon the edge of the opening in said ledge, and a slide member on said ledge comprising a plate having an aperture therein adapted in one position of the member to engage the flange member of the reservoir to hold it in position and in another position of the member to pass said flange member and to permit the removal of the reservoir.

2. In an oil stove, the combination with an oil reservoir, of supporting means therefor comprising a horizontal supporting ledge, said reservoir having a flange member rigid therewith, a seat upon said ledge, and a slide member on said ledge having an aperture therein of a size adapted to receive said flange member in one position of the slide member but being normally located out of register with said flange member whereby to hold it in position on said ledge.

3. In an oil stove, the combination with a reservoir having a discharge nozzle, means for supporting the reservoir comprising a horizontal ledge having an aperture therein, an oil well secured on the underside of said ledge and having a bottom wall, a flange member on said reservoir adapted to rest upon the edge of the aperture in said ledge and rigid with the discharge nozzle of the reservoir, a valve member in said discharge nozzle including a stem normally adapted to engage with the bottom of the well to hold the valve means inoperative, and a slide member for locking the reservoir in position comprising a plate having an aperture therein adapted in one position of the slide to pass said flange member and in another position thereof to operatively engage therewith to prevent the withdrawal thereof.

4. In an oil stove, the combination with a reservoir having a discharge outlet and an oil well, of means for supporting said reservoir with its nozzle discharging into said well comprising a bracket having a horizontal portion with an aperture therein, a part rigid with the reservoir resting upon the edge of said aperture, and a locking

slide movable longitudinally upon said bracket and adapted in one position to engage with said part to hold the reservoir in position and in another position to release 5 said part for removal with the reservoir.

5. In an oil stove, the combination with an oil well and a reservoir adapted to discharge thereto, of means for locking said reservoir in position with reference to said 10 well comprising a part rigid with the reservoir and a locking member longitudinally movable in a horizontal plane with reference to the reservoir and well and adapted in one position to engage with said part 15 to hold the reservoir in position and in another position to permit the withdrawal of said part with said reservoir.

6. In an oil stove, the combination with a frame, an oil well rigid with said frame, 20 and a reservoir adapted to discharge into said well, and having a horizontally projecting part, of means for locking the reservoir in position comprising a longitudinally slidable member engaging said well and said 25 part on the reservoir and adapted in one position thereof to permit the removal of said part with said reservoir and in another position to hold the part against withdrawal.

7. In an oil stove, the combination with 30 a frame, of a bracket mounted on the frame and comprising a horizontal plate having an aperture therein, a reservoir having a part rigid therewith and adapted to engage in said aperture, and locking means for said reservoir comprising a horizontal sliding member having an aperture therein with a portion of a size substantially less than said part whereby to hold it upon said plate and a portion of a size sufficient to pass said 40 part to permit the removal thereof with the reservoir.

8. In an oil stove, comprising a frame, an oil well at one end of said frame and having a discharge pipe rigid therewith and 45 passing through the frame, of an oil reservoir arranged to discharge into said well, and means longitudinally slidable relative

to said reservoir for locking it in position with reference to said well, said means being adapted in one position thereof to permit 50 the withdrawal of the reservoir.

9. In an oil stove, the combination with a reservoir, of means for supporting the reservoir comprising a horizontal support and a part rigid with said reservoir adapted to cooperatively engage with said support and means for locking said reservoir in position comprising a longitudinally movable member adapted to normally lock the reservoir in position on said support and 60 means for limiting the extent of movement of said member.

10. In an oil stove comprising a frame, a bracket mounted on said frame and having a horizontal portion, an oil well on the underside of said horizontal ledge, an oil reservoir having a discharge outlet arranged to discharge into said well, a member slidably engaging said ledge and adapted in its normal position to lock the reservoir against 70 withdrawal but adapted to permit such withdrawal when slid into another position, and a stop member fixed with reference to said ledge and adjacent the part upon the reservoir for limiting the movement of the 75 slide member in one direction and holding said part against movement when slid in the opposite direction.

11. In an oil stove, the combination with a horizontal supporting ledge having an oil well secured on its underside and having an opening therein, an oil reservoir having an outlet arranged to discharge through said opening into said well, and means for locking the reservoir in position upon the ledge but permitting its withdrawal therefrom comprising a slide member slidably engaging with said well and said ledge, said member having an aperture therein for permitting its movement relative to the reservoir. 90

In testimony whereof I have hereunto set my hand.

RUDOLPH HOFFMAN.
